ATTORNEYS

UNITED STATES PATENT OFFICE.

MAX HECHT, OF NEW YORK, N. Y.

DESIGN FOR A BELT ORNAMENT.

SPECIFICATION forming part of Design No. 20,368, dated December 9, 1890.

Application filed November 8, 1890. Serial No. 370,809. Term of patent 3½ years.

To all whom it may concern:

Be it known that I, MAX HECHT, a citizen of the United States, residing at New York city, in the county and State of New York, have invented and produced a new and original Design for a Belt Ornament, of which the following is a specification, reference being had to the accompanying drawing, forming part thereof.

10 The figure is a face view of the ornament, showing the design.

The leading feature of the design consists in the figure of an anchor and the representation of a rope formed into a coil on the shank

portion of the anchor. The anchor A is formed 15 with a shank B, the star-shaped crown C, the curved arms D, the triangular flukes E, the cross-piece F, and the ring or shackle G. The rope H extends from the ring G, and then forms a spirally-shaped coil H' on the shank 20 B of the anchor A.

I claim—

The design for a belt ornament, substantially as described.

MAX HECHT.
